UNITED STATES PATENT OFFICE.

FRANCIS A. STAINKAMP, OF NEW YORK, N. Y., ASSIGNOR OF ONE-HALF TO RUDOLPH DIEHL, OF NEW YORK, N. Y.

DESIGNOGRAPH.

1,254,003.

Specification of Letters Patent. Patented Jan. 15, 1918.

Application filed December 24, 1915. Serial No. 68,495.

To all whom it may concern:

Be it known that I, FRANCIS A. STAINKAMP, a citizen of the United States, residing in the city, county, and State of New York, have invented certain new and useful Improvements in Designgraphs, of which the following is a specification.

My invention relates to a designograph of the class including devices for tracing 10 curved designs on paper and the primary object of the invention is to provide a simple form of device for mechanically tracing numerous types of curves having a greater degree of complexity than is possible with 15 devices of this class now in general use.

My invention broadly includes a toggle arm type of pencil control, one or both arms of which are designed to be subjected to variable controlling factors which thus 20 cause a complexity of control resulting in the formation of both closed and open curves of a great variety of design.

A further object of my invention is to provide a device of the class described in 25 which the relation of one of the controlling members to the other may be quickly and accurately varied in its controlling effect and in accordance with some set plan without affecting the operative position of said 30 controlling elements.

I attain this object broadly not only by varying the constants which control one or both arms of the toggle pencil control but also by varying the angular adjustment of 35 the tracing table with reference to its engagement with the mechanism which controls the toggle.

Another object of my invention is to provide a device for simultaneously causing a 40 plurality of similar designs to be arranged in present relation to each other.

Incidentally, the device illustrated is intended to be assembled as one of the possible constructions which can be made from the 45 parts constituting the steel structural elements of a mechanical toy including perforated girder strips and plates, two types of which are known commercially as "Mechano" and "American model builder."

50 Various other objects and advantages of the invention will be in part obvious from an inspection of the accompanying drawings

and in part will be more fully set forth in the following particular description of one form of mechanism embodying my invention, and the invention also consists in certain new and novel features of construction and combination of parts hereinafter set forth and claimed.

In the drawings: 60 Figure 1 is a plan view of a preferred embodiment of my invention showing the table supporting frame in an adjusted dot and dash line position; and

Figs. 2 and 3 are respectively side and 65 end views in elevation of the device shown in Fig. 1.

In the accompanying drawings, there is shown an open-work main supporting frame formed of a rectangular superframe 10 and 70 a similarly shaped underframe 11 with these frame elements connected at each corner by means of vertical struts 12 all coacting and arranged to form an open box-like frame for supporting the movable parts of the device. Both the superframe and the underframe are formed of longitudinally and transversely disposed side members 13 each provided with vertically aligned pivot pin holes 14 equally spaced apart along the 80 length of each of the side members and designed to receive one or more pivot pins 15. These pins are designed to be inserted in any pair of holes and are held in position with their upper ends projecting above the side 85 members forming the superframe by means of stop collars 16 adjustably mounted on the upwardly projecting portion of the pivot pins. A work supporting table 17 is centrally mounted for rotary movement within 90 the frame and in a plane substantially on a level with the superframe. The table is arranged to receive the paper or other work upon which the design is to be made. The table and its driving mechanism are ar- 95 ranged to be supported from a table frame 18 shiftably mounted in the main supporting frame. The table frame is vertically disposed and includes upper and lower longitudinal members 19 and 20 corresponding 100 in shape to the side members of the main frame. The ends of each of the members 19 and 20 are adjustably fastened, by means of readily removable pins 21 respectively to

any of the holes 14 in the upper and lower frames. These members are preferably braced in spaced apart relation to form a unit frame by means of the vertically extending struts 22 fastened therebetween. The members 19 and 20 are provided with spaced apart holes 23 resembling the holes 13 and the struts are fastened to these members by means of screws 24 passed through one of the holes and into the ends of the struts. A vertically disposed driving shaft 25 is rotatably mounted in any of the vertically disposed pair of holes 23 and is driven through the beveled gear connection 26 from the longitudinally extending shaft 27 rotatably mounted in the struts 22. This shaft is in turn driven from the main driving shaft 28 journaled in the struts 12. An outer end of the main shaft is provided with a crank handle 29 by means of which the main shaft and parts operated thereby may be driven either in a direct or reverse direction. The connection between the main shaft 28 and the longitudinal table driving shaft 27 is preferably in the form of a friction drive 30. This drive includes a driver in the form of a disk 31 fixed to the main shaft and a round headed driven member 32 fixed to the shaft 27 in operative engagement with the disk to be driven thereby. The member 32 is adjustable relative to the axis of rotation of the disk 31 to vary the rotary speed of the table and for this purpose the shaft 27 includes a turn-buckle 33 thus providing a convenient means for varying the speed of the design table with reference to the speed of the main shaft and the pencil control actuated thereby. The design table proper is formed of a flat metal disk 34 loosely mounted on top of the shaft 25 and a wooden plate 35 fixed to the upper face of the disk and designed to have the paper 36 fastened thereto by any suitable means, such as thumb tacks 37. A driving connection is provided between the shaft 25 and the disk 34 by means of an arm 38 fixed to the shaft 25 and provided with a spring catch 39 designed to engage in any one of a plurality of centrally disposed apertures 40 arranged concentrically of the axis of the disk 34 and on the under side of the disk.

A pair of recording tables 41 and 42 are mounted in adjusted position on the supporting frame and are operatively driven from the main shaft 28. A description of either one of these recording tables will be sufficient for both it being understood that the two tables may be mounted either on the same side of the main frame or one on one side and the other on either the opposite or an adjacent side of this frame. Each of these recording tables includes a vertically extending shaft 43 adjustably mounted in any of the pair of holes 14. A disk 44 is fixed to the upper end of the shaft and above

the superframe 10. A slide bar 45 is adjustably mounted on the disk 44 and is fixed thereto in any desired adjusted position by means of a screw and slot connection 46. A rotary pivot pin 47 extends upwardly from adjacent one end of the slide bar 45 and is designed to engage with an element of the toggle pencil control hereinafter described, to cause the engaged portion thereof to travel over a circular path defined by the distance of the pin 47 from the axis of rotation of the table 41. The shaft 43 is connected to the main shaft so as to be driven thereby preferably by means of a mitered gear connection 48. This gear connection is preferably so arranged that raising the shaft 43 with its revolving pivot pin 47 will break the connection between the teeth of the gears forming the connection thus permitting either the main shaft or the record table driving shaft to be adjusted relative to each other.

Further the speed between the recording table and the main shaft may be varied by varying the speed ratio of gears making up the connection 48. In this way it is possible to cause the rotation of the recording table to be a definite function of the rotation of the work-table or a definite function of the other recording table. The placing of the design on the paper is controlled by means of a toggle pencil control formed of arms 49 and 50 pivotally connected at any point along their lengths by means of a pin 51. Each of the arms is provided with openings 52 corresponding in character to the holes 13 and each designed to be engaged either by both of the revolving pivot pins 47 or arranged so that one of the holes in one of the arms is engaged by one of the revolving pins 47 and one of the holes in the other arm is engaged by one of the fixed pins 15. The pencil control includes a pencil carriage including a bracket 53 attached by means of a pin and slot connection 54 with one of the arms 49 or 50 and in the device illustrated the bracket is attached to a projecting portion of one of the arms and to the outside of the pivotal connection between the arms. A pair of levers 55 are pivotally connected side by side to an upstanding member 56 of the bracket and designed to be adjusted vertically about horizontally disposed axes of rotation. Each of the levers is provided with a pencil band 56' designed to encircle a pencil 57 or other suitable marking device. The bands are attached by means of screws 58 to the levers. The screws may be adjusted into frictional tight engagement with the lever and band so that the pencils may be adjusted to assume any desired angle with reference to the vertical or the screws may be used merely as pivots in which case the pencil is held to the paper merely by its own weight and the weight of the 130

lever. One of the arms may be provided with a slot 59 designed to engage one of the pins 15.

In operation, and assuming that it is desired to make a definite character of curve, the resultant of two movements, one an oscillatory movement about a fixed center and the other an oscillatory movement about a center which is itself revolving, one of the 10 arms is placed on the pin 15 which has been shifted in the frame into position to bring the pencil at the desired starting point with reference to the design table. The other arm is placed upon one of the pins 47, the 15 driving shaft of which has been adjusted in the same frame into position to dispose the pencil at its desired place on the work toggle arms. The main shaft is then rotated, causing either or both of the pencils, 20 pending upon the arrangement of the arms carried by the bracket to form one or two similar tracings on the paper 36. Should it be desired however, to form a character of curve the resultant of compounding motions both of which are the result of constants which are variable, the arm engaging 25 the fixed pin 15 is shifted to the pin 47 of the other recording table, and the operation is repeated as previously described but 30 obviously giving a more complex curve. By moving the catch 39 into an inoperative position, thus disconnecting the work-table from its driving shaft, the table may be rotated upon the axis of the shaft into any 35 angular desired position. In this reset position the catch may be reset to hold the table in connected driving relation with the mechanism controlling the pencil control. The table may be reset to rotate about a new 40 axis of rotation by loosening one or the other of the pins at the opposite ends of the table frame, and adjusting the same so that the table frame will be in a new position with reference to the main frame. It is possible to make this adjustment without 45 affecting the driving connection between the main shaft and the horizontal table driving shaft due to the rounded construction of the head to the driven member 32. By adjusting the turn-buckle the speed of the work 50 table with reference to the cycle of operation of the toggle pencil control may be carried at will.

A further adjustment is provided by 55 varying the positions of the pins 47 with reference both to each other, with reference to the position of the work-table and with reference to the diameter of the circle traced by these revolving pins.

60 By means of a device of this character it is possible to design an ever-interesting toy from structural parts supplied by the structural mechanical element toys now in general use. Practically an unlimited number 65 of beautiful and unusual designs may be

formed simply by varying the positions of the toggle arms and a control for the pencil is provided which is easy and positive in its operation and any design may be repeated simply by identifying the previous positions 70 of the changeable factors and replacing the toggle arms in their previous positions.

Any desired degree of pressure engagement between the pencil and paper may be provided and by loosening the screws 58 the 75 pencils may be caused to bear lightly on the paper. A multiplicity of similar designs may be traced simultaneously by using two or more pencils thus further providing for a complication of designs. 80

While I have shown and described, and have pointed out in the annexed claims, certain novel features of my invention, it will be understood that various omissions, substitutions and changes in the form and de- 85 tails of the device illustrated and in its operation may be made by those skilled in the art without departing from the spirit of the invention.

Having thus described my invention, I 90 claim:

1. In a device of the class described, a supporting frame including a pair of members extending at an angle to each other, one of said members provided with a plurality of 95 spaced apart pin holes, a pivot pin designed to be mounted in any one of said holes, and a pencil control including a pair of toggle arms pivoted together with one of the arms pivoted to said pin in the member provided 100 with the pin holes for oscillatory movement about a fixed axis of rotation and the other arm pivotally connected to the other member.

2. In a device of the class described, a sup- 105 porting frame including a pair of mem- bers extending at an angle to each other and each provided with means for positioning a toggle controlling member along the same at different distances from the point of inter- 110 section of said members, a pencil control including a pair of toggle arms pivoted to- gether, one of said arms provided with means for pivotally connecting the same to one of said members and the other arm pro- 115 vided with means for pivotally connecting the same with the other member.

3. In a device of the class described, a supporting frame including a pair of mem- 120 bers extending at an angle to each other and each provided with means for positioning a toggle controlling member along the same at different distances from the point of inter- section of said members, a pencil control in- cluding a pair of toggle arms pivoted to- 125 gether, one of said arms provided with means for pivotally connecting the same to one of said members and the other arm pro- vided with means for pivotally connecting the same with the other member, said last 130

- named means including mechanism for causing a point on the arm controlled thereby to travel over the path of a closed curve.
4. In a device of the class described, a supporting frame including a pair of members extending at an angle to each other and each provided with means for positioning a toggle controlling member along the same at different distances from the point of intersection of said members, a pencil control including a pair of toggle arms pivoted together, one of said arms provided with means for pivotally connecting the same to one of said members and the other arm provided with means for pivotally connecting the same with the other member, said last named means including mechanism for causing a point on the arm controlled thereby to travel over the path of a closed curve, said mechanism including means for varying the dimensions of said path.
5. In a device of the class described, the combination with a recording table, of a pencil control including a pair of toggle arms pivotally connected together, a supporting frame fixed in place, means for pivoting different points along each arm of the control at different places on said fixed frame relative to a fixed point on said recording table thereby to vary the normal angle between said arm and to position the angle at different places relative to the fixed point of the turn-table and means acting on one of the arms for causing a point on the same to travel over the path of the closed curve thereby to cause a periodic variation of said angle.
6. In a device of the class described, a recording mechanism including a driven shaft, a recording table loosely mounted on said shaft, a driving connection between said shaft and table, said connection including means for engaging the table at different points in its angular adjustment on the shaft and a pencil control operatively connected to said shaft so as to be actuated therewith whereby a succeeding design may be traced on the recording table in a position displaced from the preceding similar design.
7. In a device of the class described, a driving mechanism, a recording table freely mounted for rotary movement, said mechanism including an adjustable driving connection with said table to drive the same when set in different angularly adjusted positions, means for adjusting the position of said table angularly about its axis of rotation, and a pencil control operatively connected to said mechanism to be actuated thereby in unison with said table.
8. In a device of the class described, a recording mechanism including a driven shaft, a recording table mounted for rotary movement on said shaft and provided with a plurality of spaced apart apertures arranged circularly about the axis of rotation of the table and shaft, an arm fixed to the shaft and provided with a catch for engaging in any one of said apertures whereby the table may be rotated into adjusted position without affecting the position of said shaft and co-acting mechanism operatively connected to be driven in unison with said shaft.
9. In a device of the class described, a recording mechanism including a driven shaft, a recording table mounted for rotary movement on said shaft and provided with a plurality of spaced apart apertures arranged circularly about the axis of rotation of the table and shaft, an arm fixed to the shaft and provided with a catch for engaging in any one of said apertures whereby the table may be rotated into adjusted position without affecting the position of said shaft, co-acting mechanism operatively connected to be driven in unison with said shaft and means for shifting the axis of rotation of said shaft relative to said coacting mechanism.
10. In a device of the class described, a recording mechanism including a work table mounted for rotary movement, a pencil control for moving a pencil over the work table, driving mechanism for actuating said control and said table in unison and means for shifting the axis of rotation of said table in two directions at an angle to each other without affecting the normal position of said control.
11. In a device of the class described, a pencil control including a pair of toggle arms pivotally connected together, means for pivotally mounting one of said arms at a definite point along its length for oscillatory movement about said point, a rotating design table having a fixed axis of rotation and means carried by said table and offset from the axis of rotation thereof for engaging the other of said arms at a point offset laterally of the length of said other arm.
12. In a device of the class described, a pencil control including a pair of toggle arms pivotally connected together, means for pivotally mounting one of said arms at a definite point along its length for oscillatory movement about said point, a rotating design table, a pivot pin carried by said table and offset from the axis of rotation thereof, a plate provided with a plurality of holes fixed to the other of said arms, said arm designed to be shifted about its pivotal connection with the first named arm to bring any of the holes in the plate in pivoting engagement with said pin.
13. In a device of the class described, a pencil control including a pair of toggle arms pivotally connected together, means

for pivotally mounting one of said arms at a definite point along its length for oscillatory movement about said point, a rotating design table, a pivot pin carried by said table and offset from the axis of rotation thereof, a plate provided with a plurality of holes arranged in rows both parallel to and at right angles to the length of the arm attached thereto.

10 14. In a device of the class described, a pencil control including a pair of toggle arms pivotally connected, rotary means operatively connected to each of said arms to cause the points on the arms engaged there-

15 by to travel over the paths of closed curves.

15 15. In a device of the class described, the combination of a pair of revolving members each movable about fixed points of reference and a pencil control including a pair 20 of arms pivotally connected to each other and pivoted to said revolving members.

16 16. In a device of the class described, the combination of a pair of revolving members each movable about fixed points of reference, a pencil control including a pair of arms pivotally connected to each other and pivoted to said revolving members and means associated with one of the members for varying its path of movement relative 25 to its fixed point of revolution.

17 17. In a device of the class described, the combination of a pair of revolving members each movable about fixed points of reference and a pencil control including a pair 30 of arms pivotally connected to each other and pivoted to said revolving members and

means for varying the relative position of said revolving members.

18. In a device of the class described, the combination of a pair of revolving members 40 each movable about fixed points of reference, a pencil control including a pair of arms pivotally connected to each other and pivoted to said revolving members, means for varying the relative position of said 45 revolving members and for varying the distances thereof from their fixed points of revolution.

19. In a device of the class described, a pair of designing tables mounted for rotary 50 movement and each provided with an element of a pivotal connection, means for shifting one of said elements relative to the axis of rotation and a pencil control including a toggle formed of a pair of arms each 55 arm provided with an element of a pivoted connection designed to coact with one of said first named elements.

20. In a device of the class described, a designing table including a driven shaft, a 60 plate fixed, to said shaft for rotary movement, a bar supported from said plate, a pin and slot connection between said bar and plate for fixing the bar in adjusted position on said plate and a pivot pin carried 65 by said shiftable bar and designed to engage an element of a pencil control and means for rotating said shaft.

Signed at New York city, in the county of New York and State of New York, this 70 22d day of December, A. D. 1915.

FRANCIS A. STAINKAMP.
